UNITED STATES PATENT OFFICE.

HENRY GRAFF, OF PHILADELPHIA, PENNSYLVANIA.

ADJUSTABLE ECCENTRIC.

SPECIFICATION forming part of Letters Patent No. 708,223, dated September 2, 1902.

Application filed October 8, 1901. Serial No. 77,401. (No model.)

To all whom it may concern:

Be it known that I, HENRY GRAFF, a citizen of the United States, residing at Philadelphia, county of Philadelphia, State of Pennsylvania, have invented a certain new and useful Improvement in Adjustable Eccentrics, of which the following is a specification.

My invention relates to new and useful improvements in adjustable cranks, and has for its object to provide an adjustment which can be placed in any line of shafting and which attachment carries a wrist-pin which can be adjusted so as to give more or less throw to the pitman to which it is connected.

With these ends in view this invention consists in the details of construction and combination of elements hereinafter set forth and then specifically designated by the claim.

In order that those skilled in the art to which this invention appertains may understand how to make and use the same, the construction and operation will now be described in detail, referring to the accompanying drawings, forming a part of this specification, in which—

Figure 1 represents an end elevation of my invention; Fig. 2, a section on the line 2 2 of Fig. 1, and Fig. 3 a section on the line 3 3 of Fig. 2.

In carrying out my invention as here embodied, A is a power-shaft, which shaft is separated for the purpose of attaching my invention thereto.

B represents two guide-blocks, one secured to each end of the power-shaft A by any suitable means, (here shown as set-screws C.) These guide-blocks B have vertical guideways B' formed through them.

C' represents upright slides, and these slides are adapted to rest and be guided within the guideways B' and are connected together by the wrist-pin D, which is adapted to be encircled by the end of the pitman E.

F represents slots formed through the slides C', and G represents bolts which pass through the guide-blocks B upon each side of the guideways B' and through the slot F of the slide C'. Thus the slides C' will have a vertical movement within the guideways B and will be limited only by the length of the slot F, and it will be seen that the wrist-pin B can be placed in alinement with the power-shaft A or any distance out of alinement up to a certain limit.

For the purpose of adjusting the position 55 of the wrist-pin and holding it in such a position after adjustment I provide the adjusting-screws H, which are four in number, one of said screws being threaded through the top of each of the slides C' into the slot F and the 60 other two screws being threaded through the bottom of the slides C' into the slot F. Thus two of the screws will bear against the tops of the bolts G and two against the bottom, and by unscrewing one set of screws and 65 screwing up the other set upon the opposite side of the bolts the wrist-pin can be set at whatever point desired, and the two sets of screws bearing against the bolts upon opposite sides will hold the wrist-pin in whatever position set, and as the whole attachment revolves with the power-shaft A it will transmit 70 eccentric motion to the pitman E.

The advantage of my invention is that by the use of this exceedingly simple and yet 75 durable device any amount of throw can be given to a pitman without changing from one crank to another, and this is of great advantage in machinery where a variable throw is desired, as it only requires a few minutes 80 to change or adjust the amount of throw transmitted to the pitman.

Of course I do not wish to be limited to the exact construction here shown, as slight modifications could be made without departing 85 from the spirit of my invention.

Having thus fully described my invention, what I claim as new and useful is—

In an apparatus of the character described, two guide-blocks secured upon the end of a 90 power-shaft, guideways formed in said guide-blocks, slides adapted to slide within said guideways, a wrist-pin connected to each of said slides and extending between the same, slots formed through the slides, bolts secured 95 in the guide-blocks upon each side of the slides and extending through the slot within said slide, and screws threaded through each end of the slides and adapted to bear against the bolts upon opposite sides, substantially 100 as described and for the purpose specified.

In testimony whereof I have hereunto affixed my signature in the presence of two subscribing witnesses.

HENRY GRAFF.
